Primary Examiner — Marianne Pandozzi*Assistant Examiner* — Jae Liang(74) *Attorney, Agent, or Firm* — Banner & Witcoff, Ltd.(57) **CLAIM**

The ornamental design for a container rib, as shown and described.

DESCRIPTION

FIG. 1 is a top, front, right perspective view of a container rib showing our new design;

FIG. 2 is a front, left perspective view thereof;

FIG. 3 is a front, right perspective view thereof;

FIG. 4 is a rear view thereof;

FIG. 5 is a front view thereof;

FIG. 6 is a top view thereof;

FIG. 7 is an enlarged top, front, right perspective view with unclaimed subject matter omitted thereof; and,

FIG. 8 is an enlarged right side view with unclaimed subject matter omitted thereof.

The broken lines in the drawing depict environmental subject matter only and form no part of the claimed design.

1 Claim, 7 Drawing Sheets(56)
